COMBINED BOTTLE SHIPPING AND DISPLAY DEVICE

Grover C. Hilton, Hutchinson, Kans.

Application February 24, 1948, Serial No. 10,546

2 Claims. (Cl. 206—45.14)

1

The invention has relation to improvements in means for packaging and displaying articles of merchandise, primarily bottles containing fluid cement or similar substances, and has relation in particular to improvements over the invention disclosed in my earlier application for a patent for a similar device, Serial No. 594,678, filed May 19, 1945, now abandoned.

One object of my invention is to provide a one piece and more simplified construction in which two advertising panels for the articles when placed on display are readily usable to afford protection for said articles during shipment.

Another object is to provide a simplified means of temporarily fastening and holding the two above mentioned panels together while the articles are on display.

A further object is to provide in a device of this character a more effective and secure holding means for the articles to be displayed.

Figure 1 of the accompanying drawings is a side elevation partly broken away and in section showing the device conditioned for shipment.

Fig. 2 is a top plan view partly broken away and in section.

Fig. 3 is a vertical transverse section on line 3—3 of Fig. 1.

Fig. 4 is a side elevation partly broken away and in section showing the device conditioned for displaying the articles for sale.

Fig. 5 is a perspective view showing one of the fastening means for holding the advertising panels together.

Fig. 6 is a section through the fastening means taken on line 6—6 of Fig. 4.

Fig. 7 is an elevation showing the one-piece blank used in constructing the device.

The device of the present invention differs from that of my previous one above identified, in that it may be stamped from a single substantially rectangular blank of cardboard or the like, thereby using less material and being cheaper to manufacture, it has more effective means for gripping and holding the necks of the bottles, and the construction is such that it is more easily set up in a display condition.

In the drawings above briefly described, the numeral 8 designates a horizontal rectangular base. Two lower inclined wall sections 9 are integral with the longitudinal edges of the base 8 and converge upward therefrom. Two lower vertical wall sections 10 are integral with the upper edges of the sections 9 and project upward therefrom. Openings 11 are formed in the inclined wall sections 9 to receive the lower ends of bottles or the like 12.

2

The openings 11 are formed by cutting U-shaped slits 11a in the blank as shown in Fig. 7, thereby forming legs 10a adapted to serve as supports for the upper portion of the device. These supporting legs 10a extend vertically downward from the wall sections 10 in the set-up device as shown in Fig. 3, their lower end resting on the bottom or base 8. As shown in Fig. 7 said legs 10a are cut off square but, depending upon the size of the bottle, more or less or none of the material at the free ends of these legs 10a will be removed.

Two outwardly and horizontally projecting flanges 13 are provided at the top of said lower vertical wall sections 10 and two upper vertical and centrally disposed wall sections 14 are provided rising from said flanges. Said flanges 13 are each formed by folding portions of the blank to provide a lower thickness 15a and an upper thickness 15b, said lower thicknesses 15a having their inner edges integral with said vertical wall sections 10 and said upper thicknesses 15b having their inner edges integral with said vertical wall sections 14, as shown in Fig. 3.

Notches 16 are formed in said flanges 13 to receive the necks or upper parts of said bottles or the like. The notches open through the connected outer edges of the flanges 13 and the open ends of said notches are of reduced width. The notches thus provide the flanges with yieldable clip-forming portions necessitating that the bottle necks be forced or snapped into said notches, with the result that said necks will be readily held against accidental removal.

Two panels 17 project vertically from the top of said wall sections 14, each of said panels having two foldable sections 18 and 19. The outer sections 19 have substantially straight outer edges with beveled or rounded corners.

Tongues 20 are provided in one of two upper corners of each of the two panels 17 and a slit 21 is provided in the other upper corner of each panel in such a way as to provide a slit opposite or adjacent to each of the two tongues to receive said tongues when the panels 17 are in a vertical position.

In packaging the bottles and their holding means for shipment, the panels 17 are folded outward and downward with section 18 projecting outwardly and resting on the tops of bottles 12 and section 19 projecting downwardly and resting against the sides of bottles 12, thus providing protection for the said bottles during shipment. The device and its contents may then be slipped into a suitable carton and hence easily packaged.

When the bottles and their holding means reach

the merchant, he folds sections 18 and 19 back into a vertical position, forming vertical panel 17. Tongues 20 are then folded over and inserted in slits 21 to temporarily hold the panels 17 together and in a vertical position, thus displaying any sign or advertising matter printed on one or both outer faces of the panels.

A preferred means for fastening together the various sections of the device is illustrated in Fig. 4, showing walls sections 10 fastened together by means of ordinary staples 22, wall sections 14 fastened together by staples 23, and the upper and lower portions of flanges 13 fastened together by staples 24.

The longitudinal lines 25 as shown in Fig. 7 show the points at which the blank is folded to form the set-up device.

By constructing the device from a single sheet blank considerable simplicity has been attained which has resulted in requiring less material and a saving in the expense of manufacture. The use of double thickness flanges to support the necks of the bottles has been found to be far stronger and more suitable over the previous construction. In addition, the use of the tongue and slit method to fasten the upper end portions of the panels together requires an absolute minimum of labor to set the device up for display purposes. Further, the arrangement of the tongue and slit detachable fastening means at the upper corners of the panel, has the advantage of leaving the upper edges of the two portions of the panel unattached so that a number of advertising or instruction sheets may be held between the portions with parts of the sheets projecting above the upper edge of the panel. One of such sheets may be readily pulled out by each purchaser of one of the bottles or by a prospective purchaser.

From the foregoing, taken in connection with the accompanying drawings, it will be seen that a novel and advantageous provision has been made for carrying out the objects of the invention, and while preferences have been disclosed, variations may, of course, be made within the scope of the invention as claimed.

What is claimed is:

1. A combined shipping and display device for bottles or the like made from a single sheet blank and comprising a base, two inclined lower wall sections integral with the longitudinal edges of said base and converging upward, said inclined

wall sections having openings to receive the body portions of bottles to be shipped and displayed, two lower vertical wall sections centrally disposed and in contact with each other, said wall sections having their lower edges integral with the upper longitudinal edges of said inclined wall sections, two outwardly and horizontally projecting flanges at the top of said lower vertical wall sections, two upper vertical wall sections rising from said horizontal flanges, said flanges being formed by folding portions of the blank to form lower thicknesses integral with said lower vertical wall sections and upper thicknesses integral with said upper vertical wall sections, said double-thicknesses of each flange being in contact and being formed in their folded edges with notches having reduced gripping portions through which the neck portions of the bottles may be snapped, two foldable panels integral with and projecting vertically from the upper edges of said upper vertical wall sections, said panels being foldable outwardly and downwardly to cover both the tops and the upper body portions of the bottles for protecting the same during shipment, means uniting the two thicknesses of said flanges, means uniting the two upper vertical wall sections, and means at the upper corners of the two panels for detachably uniting them when disposed vertically, said detachable means leaving the intermediate upper edges of the panels unattached between said detachable fastening means.

2. A structure as specified in claim 1, said detachable uniting means at each of the upper corners of the panels comprising a bendable tongue projecting from a corner of one panel to enter a slit in the adjacent corner of the outer panel.

GROVER C. HILTON.
